[57] CLAIM

The ornamental design for a combined transmitter and receiver for locating lost remote control units, as shown and described.

DESCRIPTION

FIG. 1 is a front, top and side perspective view of the combined transmitter and receiver for locating lost remote control units showing our new design;

FIG. 2 is a front elevational view thereof, the rear being a mirror image of the front shown in FIG. 2;

FIG. 3 is a side elevational view thereof, the side opposite being a mirror image of the side shown in FIG. 3;

FIG. 4 is a top plan view thereof; and,

FIG. 5 is a bottom plan view thereof.

FIG.2

FIG.3

FIG. 4

FIG. 5
